(57) **CLAIM**

The ornamental design for an automobile as shown and described.

DESCRIPTION

1. Automobile

1.1 : Perspective

1.2 : Front

1.3 : Back

1.4 : Left

1.5 : Right

1.6 : Top

1.1 is a front perspective view of an automobile embodying our new design; 1.2 is a front elevation view thereof; 1.3 is a rear elevation view thereof; 1.4 is a left side elevation view thereof; 1.5 is a right side elevation view thereof; and 1.6 is a top plan view thereof; this design is for a heavyweight article and therefore the bottom part of the article is omitted.

1 Claim, 6 Drawing Sheets
